UNITED STATES PATENT OFFICE.

THOMAS L. TATE, OF STEWARDSON, ILLINOIS, ASSIGNOR OF ONE-HALF TO JOHN H. FRIESNER, OF STRASBURG, ILLINOIS.

FLOOD-GATE.

1,111,723.

Specification of Letters Patent. Patented Sept. 22, 1914.

Application filed February 3, 1914. Serial No. 816,807.

To all whom it may concern:

Be it known that I, THOMAS L. TATE, citizen of the United States, residing at Stewardson, in the county of Shelby and State of Illinois, have invented certain new and useful Improvements in Flood-Gates, of which the following is a specification.

This invention relates to improvements in flood gates, and has for one of its objects to 10 simplify and improve the construction and increase the efficiency and utility of devices of this character.

Another object of the invention is to provide a simply constructed device which may 15 be erected over sloughs, creeks, or in like localities which are liable to be flooded during rainy seasons, and which will close such low places in dry weather or when the water is low, but which will be automatically opened 20 at the times of flood and without damage to the device, and will be automatically restored to operative position when the water recedes to the normal level.

With these and other objects in view the 25 invention consists in certain novel features of construction as hereinafter shown and described and then specifically pointed out in the claims; and in the drawings illustrative of the preferred embodiment of the invention. Figure 1 is a perspective view of the 30 improved device applied. Fig. 2 is a sectional elevation on the line 2—2 of Fig. 1. Fig. 3 is a sectional detail on the line 3—3 of Fig. 1.

Corresponding and like parts are referred 35 to in the following description and indicated in all the views of the drawings by the same reference characters.

The improved device comprises a supporting frame including side posts 10—11 having 40 an upper or header member 12 connected to the upper ends of the posts. The posts are designed to be inserted in the ground at the sides of the stream, slough, or other locality, and will be spaced apart a distance 45 equal to the width of the stream or slough. The supporting frame may be of any required width and varied to conform to the width of the locality to be protected.

Devices of this character are generally 50 located in the lines of fencing, and in the improved device the fence structure, represented conventionally at 13, is connected to the posts 10—11 as shown. The frame 55 members are connected and supported by

oblique braces 14—15 which are recessed into the members 10—11—12 and extend for a considerable distance above the member 12 and are firmly connected at their upper ends, as represented at 16. The braces thus perform the two-fold function of supports for the frame-work and likewise to receive guide pulleys 17 over which the releasing cords are conducted, as hereafter explained.

The gate portion of the improved device 60 comprises the vertical members 18, header member 19 and a transverse supporting member 20, the latter being located a considerable distance above the lower ends of the vertical members 18. The gate device is hing- 65 edly united to the member 12, preferably by coupled eye bolts, as represented at 21, so that the gate will swing freely from the member 12. At its upper end the gate bears 70 against the lower portions of the braces 75 14—15 and is thereby limited in its movement in one direction, or in the up-stream direction of the creek or slough. Pivoted at 22 to the inner faces of the posts 10—11 are catches 23 having inwardly directed 80 offsets 24 and inclined outer portions 25. The catches are so disposed that when in vertical position the member 20 of the gate bears against the offsets or shoulders 24, as 85 represented in Figs. 1 and 3. By this arrangement when the members 23 are in vertical position the gate is held from movement toward the down-stream of the creek or slough, while the braces 14—15 hold it 90 from movement up stream.

Extending toward the up-stream side of the frame member 12 is a bracket device 26, and pivoted at 27 in the outer end of the bracket device is a pendulum-like member 28 extended laterally at its lower end, as 95 shown at 29. The lower end 29 of the member 28 and the members 18 are substantially in alignment horizontally with the member 28 and spaced a considerable distance from the gate and its frame at the up-stream side, 100 as illustrated in Figs. 1 and 2. At its upper end the member 28 extends for a considerable distance above the pivot 27, and connected to the upper end of the member 27 are cords or cables 30 which lead over the 105 pulleys 17 and thence over additional pulleys 31 on the member 12 and thence to the outer end of the members 23 to which they are connected at 32.

With a device thus constructed when the 110

water is low in the creek or slough, the members 28 and 18 will hang in vertical position, while the water flows beneath them, the cords or cables 30 holding the members 23 in horizontal position and locking the gate members 18 from movement either in an up-stream or down-stream direction. When the water rises to an abnormal extent the current first acts upon the enlarged end 29 of the member 28 and moves the latter down stream which movement will cause the upper end of the member 28 to pull the cords or cables 30 toward the up-stream end and elevate the members 23 free from the member 20, thus releasing the gate 18-19-20 and permitting it to be moved in a down-stream direction upon its hinges 21 and thus preventing the increase of the water or the flood from injuring the gate or tearing it loose from its supports. When the water recedes the member 28 will again assume its vertical position and release the members 23 and restore them to their horizontal position, and the gate device in returning to its vertical position will bear against the inclined faces 25 of the members 23 and force the latter outwardly until the member 20 passes the shoulder 24 and permits the members 23 to return to their normal position. It will be obvious that the members 23 must be constructed of resilient material which will yield to the pressure applied thereto by the gate device in returning to its normal position.

The improved device is simple in construction, can be constructed of any required size or of any suitable material to adapt it to the width of the stream or slough to which it is to be applied and likewise to the depth of the same without material modification in the construction.

The improved device may be constructed of any suitable material, but will generally be constructed of wood, or partly of wood and partly of metal.

Having thus described the invention, what is claimed as new is:

1. In an apparatus of the class described,

a supporting frame including a transverse upper member, a gate device mounted to swing from said upper frame member in one direction, means for holding said gate from movement away from said frame, a bracket extending from said upper frame member, a member movably engaging said bracket and depending therefrom and into position to be actuated by flowing water, and connecting means between said movable member and said gate holding means.

2. In a device of the class described, a supporting frame including vertical side members and a transverse head member, diagonal braces connecting the frame side members and the head member, a gate suspended from the head member and limited in its movement by the braces in one direction, a latch device holding the gate from movement in the opposite direction, and a controlling device arranged to be actuated by an abnormal rise of water and connected to said latch device and releasing the same and permitting the gate to swing in one direction.

3. In a device of the class described, a supporting frame, a gate mounted to swing upon said frame, a latch device of resilient material pivoted upon said frame, said latch device having an intermediate gate engaging offset and inclined laterally in advance of the offset, whereby the gate is held from movement in one direction and caused to automatically displace the latch device against the resistance of its resilient portion when returning to closed position, a controlling device arranged to be actuated by an abnormal rise of water, and connecting means between the controlling means and the latch device and operating to release the latch device without resistance from the resilient portion of the same.

In testimony whereof I affix my signature in presence of two witnesses.

THOMAS L. TATE. [L. S.]
